UNITED STATES PATENT OFFICE

JOHN KARMAZIN, OF DETROIT, MICHIGAN

CENTRIFUGAL COOLING DEVICE

Application filed September 17, 1925. Serial No. 56,799.

This invention relates to improvements in cooling devices for the water used in the jacket of an internal combustion engine.

The object of this invention is to increase 5 to a maximum the actual cooling effect of the radiator while the actual exposed radiating area is considerably less than that of the ordinary radiators of the well known grid type.

To this end there is provided a circular 10 radiator in the form of a drum which is rotated at a fairly high rate of speed while the motor is running, thus greatly increasing the actual area of radiating surface, or, in other words, bringing the actual radiation 15 surface in contact with a greater area of cool air. To illustrate, let it be assumed that the actual radiation surface of the drum is two square feet and it is rotated at 800 R. P. M., the total area of air brought in contact with 20 the radiation surface of the drum is 1600 square feet per minute, since the air is changing at each instant. This is a tremendous increase of effective cooling area over the ordinary stationary radiator, the average radiation surface of which is about 50 square feet. 25

In carrying out the invention, provision is made to conduct the heated water from the water jacket of the motor to the center of the drum, from where it is forced out by the 30 centrifugal force against a circular wall of the drum the outer surface of which circular wall is exposed to the air to cool said wall, the latter cooling the water as it is brought in contact therewith.

Another feature of the invention relates to 35 means to assist in returning the cooled water to the water jacket. To this end the circular wall of the radiator flares outwardly so that the water, which is whirled around with the 40 drum is conducted along said wall by the centrifugal force, to a series of curved blades, the outer ends of which blades are arranged in a corner of the drum toward which the water is directed by said circular wall. The 45 water, as it strikes said blades, which are stationary, is diverted thereby to the center of the drum and is forced through a suitable conveyance to return it to the water jacket.

Another feature of the invention relates to 50 means to increase the cooling effect along the

circular wall. To this end said wall is provided on its outer surface with blades to agitate the air while the drum is rotating. The inner face of said wall is provided with a series of baffle plates which agitate the water as it passes along said wall. To still further increase the cooling effect of said wall, the blades and baffle plates and also said wall 55 may be composed of copper, brass or other suitable material having the property of rapidly conducting heat. 60

In the drawings,—

Fig. 1 is a side elevation disclosing an internal combustion engine and sufficient of an automobile to illustrate the application of the 65 invention.

Fig. 2 is a vertical section of the radiator, taken on the line 2—2 of Fig. 3, and showing one form of the invention.

Fig. 3 is a front elevation of the radiator. 70

Fig. 4 is a view similar to Fig. 2 showing another form of the invention.

The radiator is in the form of a drum 10 which may be located at one end of an internal combustion engine or motor 11. The invention is herein illustrated as applied to the motor of an automobile including a hood 12 under which the motor is located; said motor being supported in the usual way (not shown). The radiator or cooling drum 10 75 is supported on a shaft 13 secured to a standard 14 on the motor casing 15. In Figures 1 to 3 inclusive, said shaft has a reduced end 16 which passes through the bracket 14 and has threaded thereon a nut 17 to draw a 80 shoulder 18 of said shaft tightly against the opposite side of the bracket 14 and thus secure said shaft 13 to said bracket.

The drum is arranged to rotate while the motor is running. To this end it may be 85 provided with a pulley 19, integral with said drum, said pulley being connected by a belt 20 to a driving pulley 21 secured to the forward end of the crank shaft 22 of the motor.

The water circuit for cooling the motor 90 includes the usual water jacket or chamber 23 which fits around the upper part of the cylinder casing 24. Said water jacket is provided at the top with a duct 25 through which the water may pass when in circulation 95

down through a pipe 27 connected to a T-fitting 26. From said fitting the water passes to a fitting 28 secured to the forward end of the shaft 13 in a manner hereinafter described. The fitting 28 is provided with an inlet aperture 29 and an outlet aperture 30 which apertures are separated by a wall 31. Said apertures register with two corresponding apertures 32 and 33 respectively in the shaft 13. The heated water passes through the apertures 29 and 32 into the radiator 10 where it is caused to follow the path herein-after described and indicated by the arrows in Fig. 2 for the purpose of cooling it. The cooled water passes out of the radiator 10 through an aperture 34 extending crosswise through the shaft 13 and communicating with the aperture 33, the latter registering with the aperture 30 of the fitting 28.

From the aperture 30 the water passes through a pipe 35^b, a pipe 35 and back to the water jacket 23 through a pipe section 35^a which may be a continuation of the pipe 35 or be connected thereto in any convenient manner.

The radiator or drum 10 includes a circular rear or first wall 36 and a frusto-conical portion 37, the base of which is secured to said rear wall by bolts 38 and nuts 39. Part 30 of the frusto-conical portion 37 forms the front or second wall 40 of the radiator and has a circular or annular side wall 40^a extending outwardly and rearwardly therefrom to the rear wall 36. The drum further includes a hub 41 formed on the front wall 40 which hub engages the shaft 13 to form a bearing for one end of said drum. The pulley 19, integral with the rear wall 36, forms a bearing for the other end of the drum.

To prevent leakage of water from the bearing of the drum, stuffing boxes 42 and 43 are provided. The stuffing box 42 may include a cap 42^b, threaded over the hub 41 by which packing material 44 may be forced against the shaft 13. The stuffing box 43 may include a plug 45 through which the shaft extends, said plug being threaded into the hub or pulley 19 to press suitable packing material 46 against the shaft 13.

While the radiator or drum is being rotated at sufficiently high speed, the water coming in through aperture 32 is forced outwardly in all directions between the front wall 40 and a conical disc 47 by the centrifugal force.

The disc 47 is secured to stationary shaft 13 and its outer edge is located rather close to the wall 40 and consequently the water passes out beyond the edge of said disc in a comparatively thin film and is partially cooled. The outer edge of the disc 47 is also located near the bottom of the inclined wall 40^a and as the water passes the edge of the disc 47 it is forced along said inclined wall by centrifugal force, and is cooled in passing along said wall since said wall is exposed to the air and

moves through it at high speed, the radiator making about 800 R. P. M. To increase the cooling effect of the radiator, the wall 40^a is provided on its outer face with blades 48 extending outwardly therefrom and across the plane in which the radiator rotates, said blades being effective to agitate the air. The inner face of the wall 40^a is provided with a series of annular inwardly extending ribs 49 for a similar reason to agitate the water in its passage along the wall 40^a. Said ribs or baffle-plates are secured to the wall 40^a and form pockets 50 which catch the water and the water in its passage along said wall spills over the edge of each baffle-plate into the next pocket. To further increase the cooling effect of the radiator, the wall 40^a, blades 48 and the baffle-plates 49 may be made of copper, brass, or any other kind of metal which is a rapid conductor. The drum is vertically disposed with its front wall 40 exposed to the rush of air caused by the running of the automobile. Accordingly, the temperature of the water is also lowered while passing along the wall 40 from the aperture 32. The said front wall 40 may also be composed of copper or brass. The water, in its passage along the wall 40^a, is forced into the outer corner 51 of the drum, which corner is formed by the rear wall 36 and the inclined wall 40^a. The water 95 is cooled by the time it reaches this corner and is then conducted towards the center of the drum to the outlet aperture 33 to return it to the water jacket.

To conduct the cooled water to the center of the drum, there is provided means including a plurality of curved blades 52, secured to a disc 53, which disc forms with the rear wall 36 a chamber in which said blades 52 are located. The disc 53 is stationary and may be secured in place by a hub 54 which screws on to shaft 13 and against a shoulder 55 thereof. The outer extremities of the blades 52 are located in the corner 51 so that as the water is whirled around in said corner by the rotation of said drum, it is caught by said blades and forced inwardly along them to the center of the drum. The blades may be curved for this purpose. The inner ends of said blades 52 terminate at the aperture 34 through which the water is forced out into apertures 33 and 30 to pass back to the water jacket, as previously described. It will be understood that the blades 52, since they conduct the water to the center of the drum, constitute part of a means for circulating the water through the circuit, and may be used in lieu of the customary circulating pump.

A pump 56, herein illustrated of the centrifugal type, may however be connected, if desired, in the water circuit, in which case the intake of said pump may be connected to the pipe section 35, the outlet of the pump being connected to the pipe section 35^a, said pump being driven by the engine 11 through 130

a shaft 57 and pulley 57^a from the crank shaft of the engine.

The fitting 28 may be counterbored at 58 to fit over the end of the shaft 13 to assist in locating said fitting on said shaft. The fitting is secured to the shaft by a bolt 59, one end of which is threaded into an enlarged end 60 of a dividing wall 61 between the apertures 32 and 33 of the shaft 13. The fitting is provided with a hole 62 so that it may be slipped over the bolt and a nut 63 holds the fitting 28 tightly against the end of said shaft. The fitting 28 may be provided with tapered ends 64 and 65 so the pipe sections 27 and 35^a, which may be of rubber, may readily be slipped over said ends to connect said sections with the fitting.

As previously stated, the shaft 13 is supported in the bracket 14. It may also be supported at its forward end by a strap or bracket 66 which may be secured in any suitable manner to the frame of the car, and receives the bolt 59, the bolt being secured to said bracket 66 by nuts 67 and 68.

In the form of the invention shown in Fig. 4, the parts similar to those of Fig. 2 bear the same reference numerals with a superscript "z" and like parts bear the same reference numerals. The radiator 10^z includes the rear wall 36 and an inverted saucer-shaped member composed of the front wall 40^z and a concaved portion 40^a^z secured to said front wall in any suitable manner, and extends over the rear wall 36 where it is fastened to said wall. The bearing 42^z is similar to the bearing 42 of Fig. 2 and includes the cap 42^a threaded on the hub 41^z to press the packing 44 against the shaft. The bearing 43^z also includes a cap 45^z threaded on a hub 69 on the pulley 49^z, and packing 46. Both bearings 42^z and 43^z may be provided with bushings 70 and 71 respectively which may be of bronze or any other suitable material to withstand the wear of said bearing.

The water passage through the drum 10^z is substantially like that of Fig. 2 but the arrangements of the inlet 32^z and the outlet 33^z are somewhat different. The inlet 32^z is located at the front end of the shaft 13^z. The outlet 33^z is located at the other end of the shaft which end is connected through an elbow 72, nipple 73, elbow 74 and pipe sections 35^z and 35^a^z to the water jacket 23. To assist the return of the water to the water jacket, the pipe sections 35^z and 35^a^z are inclined downwardly towards the water jacket 23 since the water of lower temperature seeks the lowest level. The pipe sections 35^z and 35^a^z may be connected to each other by a union 75 for convenience in assembling.

The fitting 28^z may be held on the end of the shaft 13^z by the bolt 59 one end of which is threaded into a central portion 60^z of a web 76 spanning the aperture or inlet 32^z. The fitting 28^z is held in place against the

end of the shaft 13^z by a nut 67 threaded on the bolt 59.

The shaft 13^z may be held in place on the bracket 14^z which is bifurcated at 77 to form a split socket 78 to embrace the shaft 13^z and which socket may be tightened by a bolt 79 to clamp said shaft in place.

The automobile may be provided at the front with a screen 80 which may be secured in any suitable manner, and forms a perforated closure through which the air may pass to the radiator 10.

The T-fitting 26 is provided with the usual removable cap 81 for the purpose of replenishing the water circuit. The usual overflow pipe 82 is also provided, which extends from the interior of the T-fitting 26 down behind the screen 80.

The device may be operated either with or without a circulating pump of the usual type and in most instances, a pump such as illustrated at 56 will not be necessary as the rotation of the radiator will force the water along the blade 52, with equal or greater velocity than that given by the ordinary circulating pump.

While the invention has been illustrated and described in great detail, it is to be understood that it is not restricted to the details described in the specification, and that various other embodiments and modifications may be used in lieu of those illustrated without departing from the spirit of the invention, or the scope of the claims.

I claim:

1. In a radiator, the combination of a drum, said drum including a first wall, a second wall and an inclined portion on the second wall extending to and connected with the first wall, a shaft extending through the center of said drum to support it, means by which the drum is rotated about said shaft, said shaft having two apertures in communication with the interior of the drum, a pipe connection having two openings therethrough, one of said openings associated with one of the apertures in said shaft to conduct water to the interior of said drum, a disc arranged close to the second wall to conduct the incoming water to the outer edge of said second wall, whence the water is forced along the inclined portion by the centrifugal force to the first wall, a stationary disc inside of said drum and located close to the first wall, said disc being secured to said shaft and being of a diameter large enough to extend close to said inclined portion, blades on said disc extending from its periphery substantially to the center of the drum, said blades being effective to deviate the water to the center of the drum and force it through the other aperture in said shaft through the other opening in said pipe connection, means on the outer surface of the inclined portion to agitate the

- air, and means on the inner surface of said inclined portion to agitate the water.
2. In a radiator, the combination of a drum, said drum including a first end wall and a second end wall, a support for said drum extending through its center, means to rotate the drum on its support, said support having apertures in communication with the interior of the drum, through one of which water may be conducted to the interior of the drum, means to guide the water along the second wall and towards its outer edge, intermediate means to conduct the water from the outer edge of the second wall to the outer edge of the first wall and to agitate the water while being so conducted, and non-rotatable means extending along the first wall to divert the water from its outer edge to the center of the drum and to the other aperture in said support.
- 20 3. In a radiator, the combination of a drum, said drum including a first end wall and a second end wall, a support for said drum extending through its center, means to rotate the drum on its support, said support having apertures in communication with the interior of the drum, through one of which water may be conducted to the interior of the drum, means to guide the water along the second wall and towards its outer edge, intermediate means to conduct the water from the outer edge of the second wall to the outer edge of the first wall, means extending along the first wall to divert the water from its outer edge to the center of the drum and to the other aperture in said support, said intermediate means including a wall, serving to cool the water, blades on the outer face of the last named wall to agitate the air, and open plate-like members extending inwardly from the inner face of the last named wall a limited distance to agitate the water in its passage from the second end wall to the first end wall by forcing it to pass over said plate-like members against the centrifugal force.
- 40 4. A radiator for cooling water including in combination a drum, means to rotate said drum, said drum having a circular outwardly flaring cooling wall at its periphery which makes the drum of larger diameter at one end than at the other, means to conduct the water into the drum and to the part of the cooling wall of smallest diameter, the water being forced along the cooling wall by centrifugal force and non-rotatable means to catch the water at the end of the cooling wall of largest diameter and to conduct it along the wall and out of the radiator.
- 50 5. In a radiator, the combination of a water-cooling chamber having a cooling wall, means to rotate said chamber, means to conduct the water from a source into said cooling chamber, means within said chamber to circulate the water through said chamber,
- means to agitate the water over said cooling wall and means to conduct the cooled water from said cooling chamber back to the source, comprising a series of curved blades forcing the water to the center of the radiator.
- 70 6. In a water-cooling device, the combination of a drum having cooling surfaces, means to rotate said drum to cool the water, means to conduct the hot water into said drum, means to force a thin sheet of water over one cooling surface, means to agitate the water over another cooling surface and means to draw the water to the center of the radiator over a third cooling surface, and means to conduct the cooled water out of said drum while the latter is rotating, said means including a shaft for said drum upon which it may be rotated, said shaft having an inlet aperture for the hot water and an outlet aperture for the cooled water.
- 75 7. In a water-cooling device for the water of the water jacket of an internal combustion engine of an automobile, the combination of a vertically disposed drum arranged in front of said engine, a horizontal shaft to support said drum, means connected to the engine to rotate said drum, said shaft having an inlet connection from the water jacket to the interior of said drum, an outlet connection to conduct the water from the drum to the water jacket, said drum including a rear wall, a side wall and a front wall, the latter being disposed at right angles to the direction of travel of the automobile so as to be struck by the rush of air while the car is running, means located inside of said drum to conduct the incoming water along said front wall to be cooled thereby, means to agitate the water over said side wall and means to conduct the cooled water to said outlet comprising a series of curved stationary blades.
- 80 8. A radiator for cooling water including in combination a drum, means to rotate said drum, said drum having two faces of unequal diameter and an inclined wall at its periphery connecting said faces, means to conduct water into the drum at substantially the center thereof, and to the face of smaller diameter, a flexible disc adjacent said face of smaller diameter, the water being forced outwardly by centrifugal force along the smaller face in a thin sheet and along the inclined wall by centrifugal force also, and means to catch the water at the edge of the face of larger diameter and to conduct it in contact with the rear wall to the center of the drum and discharge it.
- 90 9. In testimony whereof I have affixed my signature to this specification.
- JOHN KARMAZIN.
